PRODUCTION OF CARDBOARD BOX
CUTTINGS

Arthur Ponndorf and Walter Fuhrmann, Dresden, Germany, assignors to Universelle Cigarettenmaschinenfabrik J. C. Muller & Co., Dresden, Germany

Application May 20, 1937, Serial No. 143,676
In Germany February 21, 1936

7 Claims. (Cl. 164—18)

This invention relates to a method and device for punching cuttings for cardboard boxes.

In the known devices of this class a cutting is punched out of a web of material through a die in one operation. This method is open to the objection that at high working speeds the cuttings cannot be removed from the die and piled up quickly enough.

The invention proposes a new method which permits much higher operating speeds and which consists in producing cuttings by punching off the waste portions from the web of material in two or more consecutive operations, the web remaining continuous until a cutting is separated during the last stamping operation. During the entire working process the cuttings to be produced remain in the plane of the web of material whilst the waste portions are pressed through dies.

20 The device for carrying out the method indicated comprises a punch formed of a plurality of tool parts to separate the waste material in one or more working strokes from the cutting, so that one or more cuttings are simultaneously produced which after completion are conducted away by a conveyor at a speed greater than the feeding speed of the material.

According to the invention, several conveyors may be arranged one behind the other, so that 30 the cuttings after separation from the web of material are passed out of the operating range of the device by the last conveyor. It is further possible simultaneously to produce one or more cuttings by a corresponding regulation of the feed 35 of the material.

By way of example, the invention is illustrated in the accompanying drawings, in which Figure 1 is a longitudinal section of the upper die; Fig. 2, a longitudinal section of the lower die on the lines 40 II—II, of Fig. 4; Fig. 3, a view of the upper die in the direction of the arrow A; Fig. 4, a view of the lower die in the direction of the arrow B; Fig. 5, a section on the line V—V, of Fig. 4; and Fig. 6, a view of the web of material with the waste portions and cuttings marked.

Referring to the drawings, an endless web of material 1, Fig. 6, passes between an upper and a lower die in the direction of the arrow C. In the example shown, two cuttings 2 are produced 50 at each working stroke, though it is possible of course to operate so as to produce only one cutting or more than two cuttings. Whilst the cuttings 2 remain in the plane of the web 1, the lateral waste portions 3 are punched out first. 55 During the following working stroke the waste

portions 4 are blanked and thereby the cuttings 2 separated from the endless web or strip 1.

The upper die attached to a member, not shown, carrying out an up and down motion substantially comprises a plate 5 on the underside of which 5 punching knives 6 corresponding to the shape of the waste portions 3 and punching knives 7 adapted to the form of the cuttings 4 are arranged. During the cutting stroke the knives 6, 7 enter corresponding passages 8, 9 of the lower 10 die. The lower die substantially comprises a base plate 10 which on its upper side carries the cutting plate 11 provided with passages 8, 9 and below the latter possesses the passages 12, 13 for the punched waste portions. 15

The finished cuttings 2 are removed by means of the rolls 14, 15 which are disposed in a recess 16 and at the front edge of the lower die 10 on the shafts 17 and 18. The rolls 14, 15 project with their circumference somewhat beyond the surface of the cutting plate 11 and are preferably covered with leather, etc. to insure good driving of the cuttings. 20

On the underside of the plate 16 driving means for the rolls 14, 15 are provided, which comprise 25 a shaft 20 arranged in a bearing 19 and rotated by suitable means, not shown, to rotate the roll 14 by a chain gearing 21, 22, 23. The front roll 15 either idles or is driven from the shaft 20 by a chain gearing 24, 25 in the direction of the arrow 30 30 at a speed somewhat in excess of that of the roll 14.

Directly opposite the rolls 14, 15 companion rolls 26, 27 are disposed on the upper die 5. No special drive is imparted to these companion rolls 35 35 which are arranged in the holders 28, 29 which are cushioned and displaceably guided against the action of the tension springs 30, 31 in the guides 32, 33 of the upper die. The holders 28, 29 project beyond the punching knives 6, 7 and 40 engage the cutting material first and during further descent of the upper die are pressed back against the action of their springs. On account of spring pressure, sufficient frictional force is produced between the rolls 26, 27 and 14, 15 and 45 the material to insure unfailing engagement of the finished cuttings.

In the construction shown, the endless web of material 1 is intermittently advanced by a drive, not shown, to the extent of the width of two 50 cuttings 2. During the first cutting stroke the knives 6 remove the waste portions 3 from the cutting and pass them through the openings 12 of the disc 10. At this time the knives 7 are still idling, but when the web 1 is advanced to the ex- 55

tent of two cutting widths, the half punched cuttings pass also under the knives 7. During the next stroke of the upper tool the knives 7 press the waste portions between the cuttings 2 through 5 the lower die, so that two cuttings 2 are produced. Simultaneously, the knives 6 have removed again two lateral waste portions 3 from the web 4, and at each further working stroke two cuttings will be finished.

10 We claim:

1. A method of punching out cardboard box blanks by means of punching tools which move up and down, which consists in producing at least two consecutively disposed blanks simultaneously 15 from the web of material, the front and rear limiting lines of which are of different form, removing the waste portions laterally of the web under simultaneous final shaping of the blanks at their lateral margins, retaining said blanks integral 20 with said web only by the material of the web corresponding to the different forms of the front and rear limiting lines towards the middle of the web, removing said intervening material to free two successive blanks from each other and from 25 the web, and conveying away the separated blanks.

2. A device for punching out cardboard cuttings from a web of material in which the web of material is intermittently conveyed in one direction, 30 comprising a lower die formed of a plurality of tool members arranged one behind the other in the direction of the movement of the material, an upper die for punching waste portions surrounding the cuttings, said dies being so disposed that on the first of the intermittent movements of the web, the lateral portions of the web are shaped to the final contour of the lateral sides of the cuttings under removal of the waste portions, and on the second of the intermittent 40 movements of the web the middle portions of the web which alone retain the cuttings integrally together as part of the web, are removed, said middle portions corresponding to the divergence of form of the front and rear lines of the cuttings, 45 and rollers for removing said cuttings when finally shaped.

3. A device for punching out cardboard cuttings from a web of material in which the web of material is intermittently conveyed in one direction, 50 comprising a lower die formed of a plurality of tool members arranged one behind the other in the direction of the movement of the material, an upper die for punching waste portions surrounding the cuttings, said dies being so disposed that on the first of the intermittent movements of the web, the lateral portions of the web are shaped to the final contour of the lateral sides of the cuttings under removal of the waste portions, and on the second of the intermittent movements of the 55 web the middle portions of the web which alone retain the cuttings integrally together as part of the web, are removed, said middle portions corresponding to the divergence of form of the front and rear lines of the cuttings, and a plurality of 60 conveyer devices arranged one behind the other, by which the blanks are fed in relation to one another until, after the strip of material has been separated from the last conveyer device, it is moved out of the range of operation of the apparatus.

4. A device for punching out cardboard cuttings from a web of material in which the web of material is intermittently conveyed in one direction, 70 comprising a lower die formed of a plurality of tool members arranged one behind the other in

the direction of the movement of the material, an upper die for punching waste portions surrounding the cuttings, said dies being so disposed that on the first of the intermittent movements of the web, the lateral portions of the web are shaped to the final contour of the lateral sides of the cuttings under removal of the waste portions, and on the second of the intermittent movements of the web the middle portions of the web which alone retain the cuttings integrally together as part of the web, are removed, said middle portions corresponding to the divergence of form of the front and rear lines of the cuttings, and a plurality of conveyer devices arranged one behind the other, by which the blanks are fed in relation to one another until, after the strip of material has been separated from the last conveyer device, it is moved out of the range of operation of the apparatus, said conveyer device comprising driving rolls located in the operative path and in the range of operation of the dies, and spring-urged counter rolls arranged opposite the driving rolls.

5. A device for punching out cardboard cuttings from a web of material in which the web of material is intermittently conveyed in one direction, 25 comprising a lower die formed of a plurality of tool members arranged one behind the other in the direction of the movement of the material, an upper die for punching waste portions surrounding the cuttings, said dies being so disposed that on the first of the intermittent movements of the web, the lateral portions of the web are shaped to the final contour of the lateral sides of the cuttings under removal of the waste portions, and on the second of the intermittent movements of the 35 web the middle portions of the web which alone retain the cuttings integrally together as part of the web, are removed, said middle portions corresponding to the divergence of form of the front and rear lines of the cuttings, and means for 40 conveying the cuttings comprising a plurality of rolls arranged in the lower die, and a drive for the rolls for rotating the rolls at a speed increasing in the direction of the web.

6. A device for punching out cardboard cuttings 45 from a web of material in which the web of material is intermittently conveyed in one direction, comprising a lower die formed of a plurality of tool members arranged one behind the other in the direction of the movement of the material, an upper die for punching waste portions surrounding the cuttings, said dies being so disposed that on the first of the intermittent movements of the web, the lateral portions of the web are shaped to the final contour of the lateral sides of the cuttings under removal of the waste portions, and on the second of the intermittent movements of the web the middle portions of the web which alone retain the cuttings integrally together as part of the web, are removed, said middle portions corresponding to the divergence of form of the front and rear lines of the cuttings, and means for conveying the cuttings comprising a plurality of rolls arranged in the lower die, a drive for the rolls for rotating the rolls at a speed increasing in 65 the direction of the web, and companion rolls in the upper die cooperating with said first rolls, cushioned and freely rotatably disposed therein.

7. A device for punching out cardboard cuttings from a web of material in which the web of material is intermittently conveyed in one direction, 70 comprising a lower die formed of a plurality of tool members arranged one behind the other in the direction of the movement of the material, an upper die for punching waste portions surround- 75

ing the cuttings, said dies being so disposed that on the first of the intermittent movements of the web, the lateral portions of the web are shaped to the final contour of the lateral sides of the cuttings under removal of the waste portions, and on the second of the intermittent movements of the web the middle portions of the web which alone retain the cuttings integrally together as part of the web, are removed, said middle portions corre-

sponding to the divergence of form of the front and rear lines of the cuttings, rollers for removing said cuttings when finally shaped, and means for rotating said rollers so as to move the cuttings away from the dies at a greater speed than the speed of movement of the web. 5
